UNITED STATES PATENT OFFICE.

WEBSTER C. ESTES, OF FLATBUSH, NEW YORK.

DESIGN FOR A BOX.

SPECIFICATION forming part of Design No. 19,417, dated November 12, 1889.

Application filed October 19, 1889. Serial No. 327,578. Term of patent 7 years.

To all whom it may concern:

Be it known that I, WEBSTER C. ESTES, a citizen of the United States, residing at Flatbush, in the county of Kings and State of New York, have invented and produced a Design for a Wooden Box, of which the following is a specification.

In the drawing the design of my box is represented by an elevation. The general shape of this box is cylindrical, and the top end is dome-shaped at A, with ribs B and C, and the base portion of the box is ornamented

by the convex ribs D E and cove F, the whole forming an artistic design.

What I claim is—

The design of the shape and configuration of a box herein shown and described.

Signed by me this 12th day of October, 1889.

WEBSTER C. ESTES.
